UNITED STATES PATENT OFFICE.

EVERETT W. HARMON, OF SHOFFNER, ARKANSAS.

LUBRICATING-PUMP.

1,209,433.

Specification of Letters Patent. Patented Dec. 19, 1916.

Application filed April 7, 1916. Serial No. 89,628.

To all whom it may concern:

Be it known that I, EVERETT W. HARMON, a citizen of the United States, residing at Shoffner, in the county of Jackson, State 5 of Arkansas, have invented certain new and useful Improvements in Lubricating-Pumps; and I do hereby declare the following to be a full, clear, and exact description of the invention, such as will enable others 10 skilled in the art to which it appertains to make and use the same.

This invention relates to improvements in pumps, and particularly to oil pumps.

One object of the invention is to provide 15 an improved operating mechanism for a pump used in connection with lubricating systems on engines.

Another object is to provide a construction whereby the stroke of the pump will be 20 constant so as to feed the oil to the proper parts of the engine without flooding.

Other objects and advantages will be apparent from the following description when taken in connection with the accompanying 25 drawing.

In the drawing: Figure 1 is an elevation of my lubricating pump shown in connection with a portion of an engine; Fig. 2 is an enlarged vertical section on the line 2—2 30 of Fig. 1; Fig. 3 is a vertical section on the line 3—3 of Fig. 2; Fig. 4 is a vertical section on the line 4—4 of Fig. 2.

Referring particularly to the accompanying drawing, 10 represents a portion of the 35 cylinder of an engine, and 11 the crank shaft thereof. Mounted on the cylinder is a receptacle 12, which is adapted to contain the lubricating oil. Disposed transversely through the lower portion of the receptacle 40 is a shaft 13, one end being rotatably mounted in a cap nut 14, and the other passing through the packing gland 15. This last-named end of the shaft is provided with an angularly extending arm 16 which is connected to an eccentric 17 on the crank shaft, by means of a connecting rod 18. Adjacent the shaft 13, within the receptacle, and having its opposite ends mounted in bearings 19 is a second shaft 20, the said bearings 45 being similar in construction to the bearings 14. Loosely mounted on the shaft 13 are two pinions 21 and 22, the former of which is a ratchet pinion having the teeth on its side face as clearly shown at 23. 50 Formed integrally on the opposite face of

the pinion 21 is a smaller pinion 24, which meshes with a pinion 25 loosely mounted on the shaft 20. This pinion 25 has a smaller integral pinion 26 which meshes with the before-mentioned pinion 22. This pinion 22 is 60 similarly formed with a smaller pinion portion 27 meshing with a pinion 28 which is keyed on the shaft 20. Adjacent the pinion 21, and rigidly secured on the shaft 13 is a sleeve 29 which is formed with an enlargement 30 65 on one side, and formed longitudinally in this enlargement is a bore 31, within which is seated a coil spring 32. Slidably disposed in this bore, and normally urged outwardly by this spring is a plunger pawl 33, the 70 outer end or nose of which engages with the ratchet teeth of the pinion 21.

On the shaft 20 are the oppositely extending eccentric blocks 34, over which are engaged the yoke straps 35. Connected to one 75 side of each of these yoke straps is a piston rod 36, each extending into a cylinder 37 mounted in the receptacle, and connected to a plunger head 38. Each of these cylinders is formed with an inlet opening 39 which 80 draws oil from the receptacle thereinto. A discharge pipe 40 is connected to the outer end of each of the cylinders, and in each of these pipes is a check valve 41. These pipes are connected to a stand pipe 42 which conveys the oil to the different moving parts of the engine. 85

It will thus be seen that by means of the eccentric 17 and connecting rod 18, rocking motion will be imparted to the shaft 13 causing the pawl 33 to engage with the teeth 23 and move the pinion 21 in one direction, but to slide idly over the teeth when the shaft is rocked in the opposite direction. This communicates intermittent rotary motion to the pinion 21 which transmits this rotary motion to the pinions 24, 25, 26, 22 and 27 to the pinion 28 which rotates the shaft 20. This moves the eccentric blocks 34 and through their engagement with the yoke strap 35 reciprocates the plungers or pistons 38. This oil in the receptacle is sucked into the cylinders 37 and then driven out by the plungers or pistons, in a slow and constant manner. Each of the plungers or pistons is equipped 95 with two packing rings 38'. 100

Mounted on the bottom of the receptacle is a casing 43 in which is disposed a spring-pressed pawl 43', said pawl engaging with the side teeth of the pinion 21 to hold said 110

pinion against retrograde movement when the member 30 moves backwardly in gaining a new grip on the teeth.

The arm 16 is formed with a plurality of 5 openings 16' by means of which the link 18 can be adjusted thereon. Thus the stroke of the arm can be regulated, and as a consequence the strokes of the pistons 38.

What is claimed is:

- 10 1. A lubricant pumping device comprising a lubricant container, pumps in the container for forcing lubricant from the container, a rotary shaft for driving the pumps, an oscillatable shaft, driving connections between 15 the shafts comprising a ratchet element, a pawl carried by the oscillatable shaft and engaging the ratchet element, and a lever carried by the oscillatable shaft for moving the said shaft.

Copies of this patent may be obtained for five cents each, by addressing the "Commissioner of Patents, Washington, D. C."

2. A lubricant pumping device comprising 20 a lubricant container, pumps in the container for forcing lubricant from the container, parallel shafts in the container, intermeshing loosely mounted gears on the shafts, means on one of the shafts for actuating the pumps, a rigidly mounted gear on the pump shaft, one of the loose gears being formed with ratchet teeth, an oscillatable member mounted on the other shaft, a spring-pressed pawl for the ratchet teeth 25 carried by the oscillatable member, and means for moving the oscillatable member.

In testimony whereof, I affix my signature, in the presence of two witnesses.

EVERETT W. HARMON.
